UNITED STATES PATENT OFFICE.

JUAN H. REECE, OF JOLIET, ILLINOIS, ASSIGNOR TO HORACE FRED HUMPHREY AND HARRY B. HUMPHREY, COPARTNERS, DOING BUSINESS UNDER THE FIRM NAME OF HUMPHREY & SONS, OF JOLIET, ILLINOIS.

GRINDING-MILL.

No. 827,883.

Specification of Letters Patent.

Patented Aug. 7, 1906.

Application filed April 18, 1904. Serial No. 203,711.

To all whom it may concern:

Be it known that I, JUAN H. REECE, a citizen of the United States, residing at Joliet, in the county of Will and State of Illinois, have 5 invented certain new and useful Improvements in Grinding-Mills, of which the following is a specification.

This invention relates to grinding-mills, and refers particularly to the improvements 10 in such mills herein shown and described.

In the accompanying drawings, Figure 1 is a vertical central section through a grinding-mill embodying the features of this invention. Fig. 1^a is a perspective view of the 15 center post and the clamping-collar thereon, the adjusting means in said center post being shown in dotted lines. Fig. 2 is a top plan view of the pinion-carrying ring with sweep attached, and Fig. 3 is a similar view of the 20 base or supporting-spider.

In the construction of a grinding-mill embodying my invention I provide a supporting-spider A, comprising four arms A', to the under side of each of which arms near its 25 outer end is secured a leg A² by means of a bolt A³. The outer extremities of the arms A' are provided with elongated openings A⁴ for receiving pivot-bolts A⁵, upon which bolts and above said arms are rotatably supported 30 four bearing-rollers A⁶. At its center the spider is provided with an opening A⁷, having rectangular pockets A⁸ in its peripheral walls. Intermediate the center of the spider and the outer ends of the arms A' a lower 35 gear-ring A⁹ is formed, preferably integral with the spider A. Upon the under side of the spider A is cast a lug A¹⁰ for a purpose to appear hereinafter.

A center post B extends through the opening A⁷ of the spider A and is secured therein by means of the lugs B' and B², formed integral with said center post and corresponding 40 in number and location with the rectangular pockets A⁸ in the opening A⁷. The center post B is inserted into the central opening A⁷ and rotated slightly relative to said spider until one of the lugs B² comes in contact with the lug A¹⁰ on the spider, thus holding the post B from further rotation. The 45 upper portion of the post B is of a diameter somewhat smaller than the lower portion and at its upper end is provided with the screw-threads B³. The upper part of the

lower portion of the post is squared, as at B⁴, and is provided with a transverse opening B⁵. 55 The post B is hollow and open at both ends. A cross-bar B⁶ lies within the opening B⁵ in the post B and is adapted to have a slight vertical movement in said opening. This cross-bar is provided with a vertical opening 6c B⁷ and with a transversely-extending rectangular pocket B⁸. B⁹ indicates grooves cut in the opposite sides of the post B to receive keys for preventing rotation of the breaker-head mentioned hereinafter. 65

An inner reducing-ring C of conical form has a center hub C', provided with an opening C², corresponding in size and form with the squared portion B⁴ of the center post B. The hub C' is adapted to rest upon the upper 70 edge of the supporting-key B⁶. Upon the outer face of the ring C a series of reducing-ribs C³ is formed, which ribs are integral with said ring.

An inner grinding-ring D is secured to the 75 lower edge of the reducing-ring C by means of bolts D', passing through suitable openings in said grinding-ring and the flanges of said reducing-ring.

An outer reducing-ring E is rotatably 80 mounted, by means of its integral hub E', upon the upper cylindrical portion of the center post B, the ring E being connected to its hub E' by means of arms E². Upon its interior sides the ring E is provided with reducing-ribs E³, corresponding with the similar ribs C³ of the reducing-ring C. Upon the upper 85 side of the arms E² are upwardly-extending breaker-fingers E⁴. The ring E has a peripheral flange E⁵, to which by means of the 90 bolts E⁶ a hopper E⁷ is secured. The lower edge of the outer reducing-ring E is provided with an outwardly-extending annular flange E⁸, upon the outer periphery of which is fixed an upper gear-ring E⁹ of substantially the 95 same diameter and corresponding in position with the lower gear-ring A⁹.

An outer grinding-ring F, corresponding in form with the inner grinding-ring D, is secured to the under side of the periphery of the ring E by means of bolts F', passing through suitable openings in the ears F². 100

A breaker-head comprising the hub G and the radiating arms G' is mounted upon the center post B and held from rotation by 105 means of keys g, lying within the grooves B⁹.

in said post and corresponding grooves g' in said head. The lower side of each of the arms G' is provided with a breaker-finger G^2 , lying beside and adapted to be passed by the breaker-fingers E^3 upon the upper side of the outer reducing-ring E . A series of balls H is placed in a ball-race H' , formed between the hub E' of the reducing-ring E and the under face of the head G . This ball-bearing is adjusted by means of a two-part jam-nut H^2 , the parts of which nut are secured together by the tightening-bolts H^3 .

An adjustment between the grinding-rings D and F is secured by means of a hand-wheel I . This hand-wheel has a hub I' adapted to rest upon the upper end of the post B , into which hub is rigidly fitted a bolt I^2 , (as by casting the hub about the head of said bolt,) said bolt extending downwardly within the interior of the post B and being screw-threaded at its lower end to receive a nut I^3 , which nut is adapted to lie within the pocket B^8 in the cross-bar B^6 .

To drive the outer reducing-ring E and grinding-ring F , I provide a bull-wheel J , having suitable openings J' therein for receiving pinions J^2 , rotatably mounted upon pivot-bolts J^3 in said bull-wheel. Upon the periphery of said bull-wheel is formed a track j , adapted to roll in contact with the bearing-wheels A^6 , carried by the arms A' of the spider A , to steady said bull-wheel and keep it in a central position with relation to the post B . The pinions J^2 mesh with the lower gear-ring A^9 and the upper gear-ring E^9 . A sweep J^4 , by means of which horse-power may be utilized to operate the mill, is secured to the bull-wheel in any suitable manner, a drag-bar J^5 being provided in this instance as a part of said securing means.

J^6 is a lead-pole to which the horse used to operate the mill may be hitched.

Motion imparted to the bull-wheel J rotates the pinions J^2 , and the lower gear-ring A^9 being stationary the upper gear-ring E is driven at double the speed of rotation of said bull-wheel. When the parts are in proper adjustment, grain—as, for instance, ear corn—is placed within the hopper. The bull-wheel J is rotated and with it the reducing-ring E and the breaker-fingers E^4 . The ears of corn lying between adjacent breaker-fingers E^4 and G^2 will be broken into pieces between said fingers, and these pieces will descend into contact with the reducing-ribs E^2 and C^3 of the reducing-rings E and C , where said pieces will be further reduced in size. As soon as said pieces are fine enough they will descend into the space between the grinding-rings D and F , the outer one, F , of which is rotated with the reducing-ring E , and here the pieces of cob and kernels of grain will be ground to any degree of fineness necessary within the limits of the mill. The fineness of the product of the mill is regulated

by turning the hand-wheel I , which results in a rotation of the rod I^2 within the nut I^3 and causes the inner reducing-ring C and grinding-ring D to be drawn nearer to or farther from the corresponding reducing-ring E and 70 grinding-ring F . The balls H within the raceway H' reduce friction between the outer reducing-ring E and the breaker-head G , and the wide bearing of the outer reducing-ring and the outer grinding-ring (they being rotatably carried by the pinions J^2) gives the mill great power and rigidity. 75

My invention is not restricted to the precise construction and arrangement of parts shown and described herein, as such construction and arrangement may be modified or varied by those skilled in the art without departing from the spirit and scope of my invention.

I claim as my invention—

1. In a grinding-mill, in combination, a supporting-frame comprising a hollow center post having a square portion and a transverse opening therein; a cross-bar in said transverse opening; a non-rotatable grinding member supported by said cross-bar upon said square portion of said post; a rotatable grinding member coacting with said first-mentioned grinding member; and means for moving said cross-bar longitudinally of said center post.

2. In a grinding-mill, in combination, a supporting-frame comprising a spider having a central opening with pockets in its peripheral walls; a center post provided at its lower end with two peripheral rows of lugs adapted to enter said pockets; means for locking said center post from rotation with relation to said spider; and coacting grinding members supported and guided by said center post,

3. In a grinding-mill, in combination, a supporting-frame comprising a spider; a lower gear-ring secured with relation to said frame; a bull-wheel having pinions adapted to mesh with said lower gear-ring; idler-rollers adjustably mounted upon the arms of said spider to rotate in a horizontal plane and adapted to roll in contact with the periphery of said bull-wheel; an upper gear-ring supported by said pinions; a grinding member carried by said upper gear-ring and secured rigidly thereto; and a non-rotatable grinding member coacting with said first-mentioned grinding member.

4. In a grinding-mill, in combination, a supporting-frame comprising a spider; a lower gear-ring formed integral with said spider; a bull-wheel having pinions adapted to mesh with said lower gear-ring; idler-rollers rotatably mounted on the arms of said spider and adapted to roll in contact with the periphery of said bull-wheel to hold said bull-wheel central of said lower gear-ring; an upper gear-ring supported by said pinions; a grinding member carried by said upper gear-

ring and secured rigidly thereto; and a non-rotatable grinding member coacting with said first-mentioned grinding member.

5. In a grinding-mill, in combination, a supporting-frame comprising a spider, said spider having a central opening therein; a lower gear-ring formed integral with said spider; a center post having lugs thereon adapted to support said post in the central 10 opening of the spider; a pinion adapted to mesh with said lower gear-ring; a grinding member having a gear connection with said pinion; said center post extending through and forming the rotative center of said grinding member; and a non-rotatable grinding member coacting with said first-mentioned grinding member.

6. In a grinding-mill, in combination, a supporting-frame comprising a spider, said frame having a central opening therein; a lower gear-ring fixed with relation to said frame; a center post having means thereon for supporting said post in the central opening of the frame, said center post having a 25 square portion; a pinion adapted to mesh with said lower gear-ring; an outer grinding member having a gear connection with said pinion; said center post extending through and forming the rotative center of said grinding member and an inner non-rotatable grinding member adjustably supported upon the square portion of said center post.

7. In a grinding-mill, in combination, a supporting-frame comprising a center post and a lower gear-ring; an inner reducing-ring non-rotatably mounted on said center post; an inner grinding-ring secured to said inner reducing-ring; an outer reducing-ring, said center post extending through and forming 35 the rotative center of said reducing-ring; an outer grinding-ring secured to said outer reducing-ring; an upper gear-ring secured to said outer grinding-ring; a bull-wheel having

pinions adapted to mesh with said gear-rings; means for moving the inner reducing-ring 45 and inner grinding-ring toward or away from the outer reducing-ring and outer grinding-ring; a non-rotatable breaker-head; and a ball-bearing between said breaker-head and said outer reducing-ring.

8. In a grinding-mill, in combination, a supporting-frame; a lower gear-ring formed integral therewith; a bull-wheel having openings therein; and a track upon its periphery; a shaft supported at its ends in the opposite 55 side walls of each of said openings; a pinion rotatably supported on each of said shafts and adapted to mesh with said gear-ring; idler-rollers mounted on said supporting-frame to rotate in a horizontal plane and 60 adapted to roll in contact with the peripheral track of said bull-wheel to hold said bull-wheel central of said lower gear-ring; an upper gear-ring supported by said pinions; a grinding member carried by said upper gear-ring and secured rigidly thereto; and a non-rotatable grinding member coacting with said 65 first-mentioned grinding member.

9. In a grinding-mill, in combination, a supporting-frame comprising a hollow center 70 post having a square portion and a transverse opening therein; a cross-bar in said transverse opening; a non-rotatable grinding member supported by said cross-bar upon said square portion of said post; a second 75 grinding member rotatably mounted upon said center post; a non-rotatable breaker-head having a screw-thread connection with said center post; and a ball-bearing between said breaker-head and said second grinding 80 member.
